UNITED STATES PATENT OFFICE.

AUGUST F. HABENICHT, OF TINLEY PARK, ILLINOIS.

CONTROLLING APPARATUS FOR AIR-PRESSURE SYSTEMS FOR PUMPS.

Application filed October 29, 1921. Serial No. 511,406.

To all whom it may concern:

Be it known that I, AUGUST F. HABENICHT, a citizen of the United States, residing at Tinley Park, in the county of Cook and 5 State of Illinois, have invented certain new and useful Improvements in a Controlling Apparatus for Air-Pressure Systems for Pumps, of which the following is a specification.

- 10 This invention relates to new and useful improvements in an air pressure pumping apparatus, which, while it is more particularly intended for use in pumping water from earth wells and cisterns, yet it is applicable for use in pumping water or liquids from various kinds of containers, whether located above ground or below the same, and has for its principal object to provide a pneumatically operated pumping apparatus 15
- 20 which shall be automatic and efficient in its operation, simple and inexpensive in construction and installation, strong and durable.

Other objects and advantages of the invention will be disclosed in the following description and explanation.

The invention consists in certain peculiarities of the construction, novel arrangement and combination of the various parts 30 thereof as will be hereinafter more fully set forth and specifically claimed.

In the accompanying drawings, which serve to illustrate an embodiment of the invention—

35 Fig. 1 is a general or diagrammatic view of the apparatus showing it installed in connection with an earth well, with its parts in their operative positions for forcing or pumping water from the well.

40 Fig. 2 is an enlarged view partly in section and partly in elevation taken on line 2—2 of Fig. 3, looking in the direction indicated by the arrows, showing certain parts of the apparatus mounted on a suitable support therefor, and in the positions illustrated in Fig. 1.

45 Fig. 3 is a view of like parts in similar positions looking in the direction of the pressure controlling cylinder mounted on said support.

50 Fig. 4 is a similar view to Fig. 2 but showing by continuous lines about the positions the parts will occupy when air pressure is shut off from the source of supply and is being exhausted from the submerged air tank in the well.

Fig. 5 is an enlarged view of a portion of the supporting frame of the apparatus and the valve casing for the valves of the supply pipe and exhaust outlet. 60

Fig. 6 is an enlarged vertical sectional view taken on line 6—6 of Fig. 4 of a needle valve and its casing carried by the pressure controlling cylinder, and

Fig. 7 is a sectional view of a portion of the air tank or vessel located within the well and a part of the air outlet pipe leading from said tank showing the means for supporting a float in said tank and for guiding a needle valve carried by said float for co-operation with the said air outlet pipe. Said view is taken on line 7—7 of Fig. 1. 65

70 Corresponding numerals of reference refer to like parts throughout the different views of the drawings. 75

Referring now more particularly to Fig. 1 of the drawings, the reference numeral 10 designates a water or liquid container such as a well, in which is suspended so as to preferably be entirely submerged in the 80 water 11 of said container, a tank 12 which is provided in its bottom with a port or opening 13 having around the same on the upper surface of said bottom a valve seat 14 to co-act with a gravity valve 15 for the purpose of admitting water to said tank. The valve 15 is surrounded by a perforated cage 16 to prevent the accidental dislocation of said valve and to avoid its being interfered with by a float 17 which is located in the 85 tank for the purpose to be presently explained. Located near the well or container is a large tank or vat 18 containing compressed air, which may be supplied thereto by any suitable means, for use for a considerable length of time. Leading from this vat 18 is a pipe 19 which is equipped with a pressure reducing valve 20 of the ordinary or any well known construction and communicates with a valve casing 21 which 90 forms a part of a larger valve casing 22 which latter casing is mounted on a suitable upright support 23 located near the well or liquid container 10 and supported in any suitable manner. The valve casing 21 has 95 a port 23 leading to the casing 22, which port is surrounded by an upwardly extended valve seat 24 for co-operation with a valve 25 the stem 26 of which is vertically mounted on a bar 27 hinged or loosely connected at one of its ends for vertical movement to a screw 27^a or other suitable pro-

100

105

110

jection depending from the upper surface of the valve casing 22 near one end thereof. The valve casing 22 is provided on its upper surface near its end opposite the member 27^a with an exhaust valve casing 28 which is provided with exhaust ports 29 and has vertically and slidably mounted therein a valve stem 30 which carries on its lower end a valve 31 to close the valve seat 32 of the casing 28.

Depending from the valve 31 is an extension 33 which is reduced towards its lower end and provided on said end with a head or enlargement 34. The bar 27 which carries the valve stem 26 is provided with an open ended slot 35 at its free end for loose engagement with the reduced portion of the extension 33 of the exhaust valve. The upper end of the valve stem 30 is provided with a head 36 and just below the stem with an enlargement or projection 37 between which head and enlargement is located one end of a lever 38 which is fulcrumed on the lower portion of the support 23 and is adapted to operate in a slot 39 in said support. That end of the lever 38 interposed between the head 36 and enlargement 37 of the valve stem 30 is provided with an open ended slot 40 for the reception and operation of said valve stem.

Leading from the end of the valve casing 22 opposite the support 23 is a pipe 41 which is extended through the cover 42 of the well or water container 10 and communicates at its lower end with the upper end of the tank 12 to which end of said tank it is secured in such a manner as to assist in supporting the same. This last mentioned pipe is employed for conveying compressed air from the valve casing 22 to the tank 12 and may be fixed to the cover 42 of the water container in any suitable manner so as to assist in supporting the said tank. The upper portion of the support 23 is deflected as shown and has mounted on its upper end a bracket 43 in which is journaled a pulley 44 over which is extended a cable or cord 45 which supports at its lower end a rod 46 which has mounted thereon a weight 47 and which rod extends into a vertically disposed guide 48 mounted on a bracket 49 with which the support 23 is provided at a suitable distance above its lower end.

Slidably mounted on the lower end of the rod 46 is another weight 50 which is adapted for vertical movement in the guide 48 and in order to restrict its movement in one direction with respect to the rod 46, said rod is provided with an enlargement 51 on its lower end to engage the weight 50 when said rod is in its lowermost position, as shown in Figs. 1 to 3 inclusive of the drawings. The cable or cord 45 is extended over another pulley 52 journaled on a bracket 53 supported on the upper portion of the support

23. That end of the cable 45 adjacent the pulley 52 has secured thereto at about its middle a cross-piece 54 from which depend a pair of connections 55 which are connected at their lower ends to a cross-piece 56 in such a way that the connections 55 will stride the pressure controlling cylinder 57 which is vertically mounted on the support 23 at a suitable point thereon. The cross-pieces 54 and 56 are disposed in parallelism with one another in such a manner that their path of travel will diametrically intersect the cylinder 57 in the operation of the apparatus.

Extended from the upper end of the cylinder 57 is a pipe 58 which extends through the cover 42 of the well or water container as well as to the top of the tank 12 to which top it is connected by means of a valve casing 59 in such a way as to assist in supporting said tank, it being understood that the pipe 58 is suitably fixed to the cover of the well through which it is extended. The valve casing 59 is provided with ports 60 and 61 with which a needle valve 62 co-operates to open and close the same. This needle valve, as is clearly shown in Figs. 1 and 7 of the drawings, constitutes a part of the supporting rod 63 for the float 17, which float is fixed on the lower portion of said rod to the end, that in the movement of the float, the valve 62 which extends into a suitable opening in the valve casing 59, will be actuated so as to open and close the port 60, thereby shutting off or permitting flow of air from the tank 12 to and through the pipe 58 to the upper end of the pressure controlling cylinder.

The pipe 58 is provided near said cylinder with a check valve 64 of any well known type. Extended through the cover of the well or water container 10 is a water service pipe 65 which may be equipped with a branch pipe 66 and a faucet 67 for drawing water from the tank 12, into which the pipe 65 is extended to a point near the bottom of said tank. This pipe 65 is also so connected to the cover 42 and the top of the tank 12 as to assist in supporting said tank. Fixed on the pipe 65 at a suitable point above the float 17 is one end of an arm 68 the other end of which is provided with a sleeve 69 through which the rod 63 of the float is extended for vertical movement. This rod is provided just above the upper end of the sleeve 69 with a projection 70 to contact with the sleeve 69 so as to restrict the downward movement of the rod 63 and the float which it carries, but so as to permit sufficient movement of said rod to allow air from the tank 12 to pass through the ports 60 and 61 into the pipe 58 and from thence into the pressure controlling cylinder.

The upper end of the cylinder 57 has mounted thereon a valve casing 71 which is

provided with a valve seat 72 for the needle valve 73 and with ports 74 and 75, the latter of which leads from the valve seat into said cylinder. The valve 73 is adjustably mounted in the casing 71 so as to regulate the quantity of air which passes from or into the cylinder. Located in the cylinder for reciprocatory movement is a piston head 76 the piston rod 77 of which extends through the bottom of the piston and is connected at its lower end to the cross-piece 56 midway between the connections 55 which unite said piece to the cross-piece 54 which is located and operates above the upper end of the cylinder. By this arrangement it is manifest that the piston rod 77 will be vertically guided in its movements so that there will be no lateral movement thereof.

Fulcrumed on one side of the bracket 49 which supports the guide 48 for the weight 50 is a gravity actuated bell-crank-lever 78, the longer arm of which is provided with an outward extension 79 having an open ended slot 80 for the reception and operation of the piston rod 77. The shorter arm 80^a of the lever 78 is provided with a hook 81 which is adapted, when the lever is moved by its gravity to the position shown in Fig. 4 of the drawings, to pass through a slot 82 in the guide 48 and engage a notch or opening 83 in the side of the weight 50 adjacent said lever so as to hold the weight 50 in its raised position. The upper end of the service pipe 65 has preferably mounted thereon an expansion chamber 84 for the purpose of retaining a reserve supply of water. The longer arm of the lever 78 is extended through a vertical slot 85 in the support 23 just below the lower end of the cylinder 57 so that the extension 79 on said lever will be in the path of the cross-piece 56 and also in order that the open slot 80 of said extension may receive the piston rod of the cylinder.

From the foregoing, and by reference to the drawings, it will be readily understood and clearly seen that, assuming the parts to be in the positions shown in Figs. 1 to 3 inclusive of the drawings, compressed air from the vat or reservoir 18 will pass through the pipe 19 and pressure reducing valve 20 which valve may be so adjusted as to permit a predetermined pressure of air to pass through the pipe 19 to the valve casing 21 and from thence through the valve casing 22 and pipe 41 to the submerged tank or receptacle 12 located as before stated, within the well or water container and at any suitable distance below the water level thereof. As the tank 12 is only partially filled with water, it is apparent that the space therein above the water will be filled with air, the degree of pressure of which will be regulated by the reducing valve 20 above mentioned. This pressure within the tank 12 against the water in said tank is considerably greater than the atmos-

pheric pressure on the main body of water in the well and consequently will force the water through the pipe 65 so as to be drawn off through the faucet 67 when the same is opened, and when it is closed, into the expansion tank 84 for a reserve supply. As soon as a sufficient quantity of water within the tank 12 is exhausted therefrom through the pipe 65 to permit the float 17 to be lowered, it is obvious that the needle valve 62 on the upper end of the float supporting rod 63 will be withdrawn from its seat sufficiently to let air escape through the ports 60 and 61 and thence through the pipe 58 to the upper end of the cylinder 57 and against the piston head 76 in said cylinder. This pressure being greater than the combined resistance created by the weights 47 and 50, will cause the piston and its rod to be quickly lowered to about the position shown in Fig. 4, in which movement the cross-piece 56 on the lower end of the piston rod 77 will strike the head 36 of the exhaust valve stem 30 and thus depress the bar 27 with which the exhaust valve 31 co-operates and thereby cause the valve 25 to be seated, (see Fig. 5) and thus shut off the air pressure to the tank 12 through the pipe 41 which leads from the valve casing 22 to said tank. At this instant pressure from the valve casing 22 will be exhausted through the port 29 of the valve casing 28 as is obvious. In the above mentioned downward movement of the piston and its rod, the cross-piece 56 will be disengaged from the extension 79 of the trip lever 78, thereby permitting said lever to assume about the position shown by dotted lines in Fig. 2, so that in the upward movement of the weight 50, which will occur during said downward movement of the piston rod, its rounded head will strike the hook 81 and cause the shorter arm and hook of said lever to be moved outwardly of the guide 48 to such a position alongside the weight 50, that the hook will automatically engage the notch or opening 83 in said weight, when the latter is sufficiently elevated, and thus hold it until the said lever is tripped by the upward movement of the piece 56 and piston rod. As the rod 46 is slidably mounted in the weight 50, it is manifest it and its weight 47 will have independent movement with respect to the weight 50, as shown in Fig. 4 by dotted lines.

In order to maintain a reserve supply of water in the expansion tank 84, the water service pipe 65 is provided with a check valve 86 which is by preference located in the water container 10 above the water level thereof.

While I have shown the tank 12 as being completely submerged in the water of the water container or well, yet I desire it to be understood that the tank 12 may be extended into the water to a suitable depth without

being completely submerged therein, and for this reason I do not desire to be limited to the submerged position of said tank except where specifically so set forth in the claims.

5 Having thus fully described my invention, what I claim as new and desire to secure by Letters Patent is—

1. In an apparatus of the class described, the combination with a body of water, of a 10 tank sunken therein and having a valve in its lower portion, a supply of compressed air connected to said tank, a valved water delivery pipe leading from the tank, a vertically supported cylinder located near the said 15 body of water, an air discharge pipe communicating with the upper end of said cylinder and with the upper portion of said tank, a needle valve casing on said pipe within the tank, a float within the tank supported for 20 vertical movement therein and carrying a needle valve for co-operation with said casing, a piston located in said cylinder for reciprocatory movement, a rod extended from the piston downwardly through the said 25 cylinder, a horizontally disposed cross-piece on the lower portion of said rod, connections extended upwardly from said cross-piece on opposite sides of the cylinder, a cross-piece uniting said connections at their upper ends, 30 a cable connected to the last named cross-piece, pulleys on the support of the cylinder for said cable, a guide on said support near the lower end of the cylinder, a rod extended into said guide and connected at its upper 35 end to the cable, a weight slidably mounted on said rod and another weight fixedly mounted thereon, a bell crank lever mounted

on said guide and having one of its arms adapted to be extended into the path of the rod carried by the piston and its other arm 40 adapted for extension into said guide and engagement with the said slideable weight, a valved casing having communication with a supply of compressed air, an air supply pipe leading from said casing to the said tank, 45 and an exhaust valve located in said casing and having its stem disposed in the path of the rod carried by the piston and the cross-piece on said rod.

2. In an apparatus of the class described, 50 the combination with a well of water, of a tank sunken in the water of said well and having a valve in its lower portion, a supply of compressed air connected to said tank, a valved water delivery pipe leading from the 55 tank, a vertically supported cylinder located near the well, an air discharge pipe communicating with the upper end of said cylinder and with the upper portion of said tank, a needle valve casing on said pipe within the 60 tank, a float within the tank supported for vertical movement therein and carrying a needle valve for co-operation with said casing, a weight-actuated piston located in said cylinder for reciprocatory movement and 65 having a piston rod extended therefrom through the lower end of the cylinder, and a valved casing having communication with the supply of compressed air, an air supply pipe leading from said casing to the said 70 tank, and an exhaust valve located in said casing and adapted to be unseated by the depression of the piston and its rod.

AUGUST F. HABENICHT.
